UNITED STATES PATENT OFFICE.

ALEXANDER BOROS AND EUGENE HEMESTRAY, OF BEAVER, PENNSYLVANIA.

HORSESHOE.

1,282,742.

Specification of Letters Patent. Patented Oct. 29, 1918.

Application filed June 21, 1918. Serial No. 241,130.

To all whom it may concern:

Be it known that we, ALEXANDER BOROS and EUGENE HEMESTRAY, subjects of the King of Hungary, residing at Midland, county of Beaver, and State of Pennsylvania, have invented certain new and useful Improvements in Horseshoes, of which the following is a specification.

This invention relates to improvements in 10 horseshoes, and particularly to types which may be attached without the use of nails or other devices entering into the hoof of the animal.

The principal object of the invention is to 15 provide a horseshoe having means by which it may be firmly attached without the use of tools and be used either temporarily or permanently.

A further object is to provide means combined with the shoe whereby it may be fitted to various sizes of hoofs so as to be held in firm engagement therewith.

These and other like objects are attained 25 by the novel construction and combination of parts hereinafter described and shown in the accompanying drawings, forming a material part of this disclosure, and in which:—

Figure 1 is a side elevational view showing 30 a shoe made in accordance with the invention.

Fig. 2 is a top plan view of the same.

Fig. 3 is a rear elevational view.

Fig. 4 is a vertical sectional view taken on line 4—4 of Fig. 1.

Fig. 5 is a fragmentary perspective view 35 showing a front part of the retaining element.

Fig. 6 is a similar perspective view showing the front part of the shoe, and

Fig. 7 is a perspective view showing one 40 of the space plates by which the shoe is adjusted to various sizes of hoofs.

The shoe body is made in the usual conventional U shape, the extreme front 10 being the bend acting as the toe of the shoe, from which extend the side elements 11 to the heels 12, which are rounded and recessed, forming forks between which are secured the reduced ends 14 of links 15, pivotally connected in the manner of hinges by 45 the pivot pins 16.

Formed in the outer ends of the links 15 are rectangular openings 18 for purposes 50 which will be further on described. Heel calks 19 are inserted near the ends 12 of the shoe, the same being pointed and extend-

ing down as usual. At the front is engaged a toe calk 20, the same being formed with or having inserted rigidly therein, a threaded stem 21 engageable within a screw-threaded opening in the toe of the shoe, while at the other end of the calk is an opening 22 receptive of a screw 23, passing downward through an opening in the toe, so as to secure the calk in a rigid manner. 60

In a recess formed in the upper surface of the shoe body, is a plate 25, rigidly secured by means of rivets 26, the plate having an upturned portion 27, its extreme point terminating in a T shaped member 28, bent 70 rearwardly at substantially right angles practically parallel with the upper surface of the shoe body.

Adapted to rest upon the upper portion of the shoe is a curved clamp element having 75 beveled walls forming a partial band 30, covering the front and sides of the shoe and having at the extreme front portion a clip 31, attached by rivets 32, the clip being bent outwardly and then upwardly, forming a 80 pair of spaced prongs 33, engageable with the stem of the T shaped members 28, thereby fastening the front of the clamp element to the shoe in a secure manner.

Secured upon the outer surface of the 85 clamp element, near the heel, are reinforcements 34, which, together with the extending portions of the clamp are united and suited to enter the rectangular openings 18, formed in the swinging links 15, and are held therein by means of cotter-pins 36, passing through openings drilled through the ends of the reinforcements so as to hold them firmly therein.

From the foregoing, it will be understood 95 that an animal's hoof may be placed upon the shoe, the clamp element adjusted thereover, and engaged so as to be locked at the front by the member 28, after which the links 15 may be turned upwardly upon their 100 pivots 16 so as to engage with the extending ends and the cotter-pins inserted, locking the entire structure rigidly together.

Should the hoof fail to fill the opening 105 between the side walls of the clamping element and top of the shoe use may be made of space plates 38, the contour of their extending limbs 39 being made in conformity with the top of the shoe and suited to be received within the clamp element, and it 110 will be understood that several of the space plates 38 may be used so as to press the hoof

outwardly against the converging walls 30 of the clamp element when it is engaged with the body of the shoe.

Having thus described our invention what we claim as new and desire to secure by Letters Patent, is:—

In a horseshoe, the combination with a U-shaped body suited to the hoof of an animal, and calks rigidly engaged at the lower side thereof, of a bracket having a T-shaped head secured to the toe of said body, said bracket extending upwardly and rearwardly, a pair of spaced links pivotally engaged in the heel portion of said shoe body, said links having openings in their upper ends, a partial clamp band having converging side and front walls, means carried at the front of

said clamp band engageable with said T-shaped head, reinforcements for said clamp band at the heel portion thereof, said reinforcements and the ends of said band being enterable within the openings in said pivoted links; means for securing said reinforcements and band ends within said links, and a plurality of spacing elements adapted to rest upon the upper surface of said shoe within said clamp element whereby the interior may be adjusted to suit the size of the animal's hoof.

In testimony whereof we have affixed our signatures.

ALEXANDER BOROS.
EUGENE HEMESTRAY.
